UNITED STATES PATENT OFFICE.

WILLIAM F. BOSSERT, OF UTICA, NEW YORK, ASSIGNOR TO THE BOSSERT ELECTRIC CONSTRUCTION COMPANY, OF UTICA, NEW YORK.

INTERIOR-CONDUIT OUTLET-BOX.

SPECIFICATION forming part of Letters Patent No. 696,710, dated April 1, 1902.

Original application filed September 16, 1901, Serial No. 75,654. Divided and this application filed January 17, 1902. Serial No. 90,145. (No model.)

To all whom it may concern:

Be it known that I, WILLIAM F. BOSSERT, residing at Utica, in the county of Oneida and State of New York, have invented certain Improvements in Interior-Conduit Outlet-Boxes, of which the following is a specification.

This invention relates to the construction of ductile-metal outlet-boxes employed in systems of interior conduits for buildings, which are struck up or drawn out by a series of progressive operations by means of dies. In the manufacture of such articles to meet the competition of business a superior box has to be made, the operations necessary to its construction have to be reduced to the lowest limit, and improved means are required in order to produce the final results with the least amount of waste of material and cost of labor.

In the present invention a flat piece of thin ductile metal is drawn into a shape having side walls, with a rim extending around the same at right angles, and a bottom. By other operations it is further pressed and the main portions of the rim trimmed off, leaving small extensions to serve as locking-ears for the cover. By another operation the box-form is forced through a special die, by which the said ears are supported and protected at right angles to the walls of the box, while the upper edges of the box are drawn upward higher than the upper face of the said ears into somewhat ragged edges. Subsequently the box is passed under a grinding-machine, and the said drawn-up ragged edges are ground off smooth and even with the said upper surfaces of the ears. The box-form is then forced through another die in such manner as to draw the said ears upward into the same plane with the walls of which they form a part, and by another operation the ears are perforated for the reception of cotter-pins.

In case the boxes are to be perforated or partially perforated for the admission of conduit-pipes the last operation effects this result. By means of this process I am enabled to produce a superior outlet-box in a very expeditious manner without breakages or waste material. Usually there has been a loss in a part of the successive operations, owing to the difficulty in preventing the ears referred to from being broken off and the box abandoned or rendered inferior during the opera-

tion of surfacing the box edges and final operations; but by the process now described the ears are preserved and the waste reduced to a minimum; and the invention therefore relates to the outlet-box made by the within-described process.

Referring to the drawings which illustrate the invention, Figures 1 and 2 are respectively face and edge views of the blank from which the box is formed. Figs. 3 and 4 are top and side views of the partly-formed box. Figs. 5 and 6 are sectional and plan views of forming-dies, with a partly-formed box between them. Figs. 7 and 8 are respectively cross-sections on lines *y* *y* and *z* *z* of Fig. 3. Fig. 9 is a sectional view of two dies to illustrate the bending of the box-ears. Figs. 10 and 11 are a plan and a sectional side view, respectively, of a completed box. Figs. 12, 13, 14, 15, and 16 are views to illustrate the formation of a cover for the box, and Figs. 17 and 18 are a plan and a side view of a box with its cover locked on.

In the drawings, *a* represents a piece of thin sheet ductile metal of the shape for drawing up into a box. It is placed across a lower die, and an upper die forces it into the lower die and produces a form *A*, such as is shown in Figs. 3 and 4, having four walls *b*, a bottom *e*, and a flange *c* at right angles to the walls, as shown in dotted lines in Fig. 3. The form *A* by another operation may have the walls drawn out to make it deeper and have the rim trimmed off close to the walls, leaving, however, portions to form two or more ears *d*. It is not necessary to refer to all of the minor operations, some of which may be partial duplicates of one another, as it will be understood by those familiar with the art that it may be better to effect one result in an article by two operations than to perform the whole by one operation, as a second operation may carry a detail with it that could not be performed by the first. At a certain point in the manipulation it becomes necessary to make the edges of the box-form *A* square and smooth in order that the box-cover may fit on tightly, as the edges are at this stage uneven. As a preliminary to this operation the form *A* is forced through a die, as shown in Figs. 5 and 6, in order that the edges *p* may be drawn out above the face

or upper surface of the ears d , as ordinarily there is not sufficient stock above the said face to finish evenly and smoothly all the way around; but in order to effect this means have to be provided to protect the ears from injury.

Fig. 6 is a plan view of the lower die C, whose area f is slightly smaller than the box-form A to be forced therethrough, and on 10 two opposite sides portions d^2 are cut through the die in the shape of the ears. The upper die B is made to fit into the upper part of the box-form and has projections t on two opposite sides, which fit into the passages d^2 of 15 the lower die. The box-form is to be placed between the dies so that the ears d are over the passages d^2 , and as the upper die B descends the projections t bear upon the ears d and protect them, while the walls of the form 20 are drawn up into edges resembling p^2 in Figs. 7 and 8, so that there is sufficient stock above the upper surfaces of the ears d . The box-form A is then brought to a grinding-machine, and the rough irregular contour 25 edges are ground off smooth and even with the upper surfaces of the ears. Subsequently the ears are turned up so to be in a plane with the walls of the box, and this is done as shown by Fig. 9, in which the upper die D 30 fits into the lower die E. The box-form A is placed in position, as shown in full lines, and as the die reaches the position shown in dotted lines e^2 and e^3 the ears d , which are at right angles to the walls b , are drawn up into 35 the position d^2 and d^3 , and as the die D carries box-form through the lower die the ears are brought up straight, and when the box-form emerges from the dies the ears are smooth and shapely. Perforations g are made 40 in the ears, preferably by punches, and the two ears of one side can be punched at the same time.

If the walls or bottom of the boxes are to be weakened in circular lines, so that portions 45 may be easily displaced when desired to introduce into the box the end of a conduit, such walls and bottom are placed between dies and said portions are displaced a distance less than the thickness of the walls, 50 after the manner shown and claimed in Patent No. 682,233, granted to me September 10, 1901, the same being indicated by the dotted-line circles in Figs. 10 and 11.

To form a cover for such a box as has been 55 hereinbefore described, a piece of thin sheet ductile metal G is cut into the same shape, having the rounded extensions h , then pressed into the form shown by Figs. 13, 14, and finally a round hole m is cut through the center of 60 the shape and the slots k are punched through opposite the extensions h .

Figs. 17 and 18 show the completed cover G upon the box A, the slots k fitting over the upright ears d and with spring or cotter pins 65 s through the perforations g to hold the cover in place.

By this construction all screws and threaded

holes are avoided and a simple economical box produced.

It will be understood that while I have illustrated the process in connection with a four-walled box that the same process can be applied to the formation of a round or any other shaped box.

The hereinbefore-described process is not 75 claimed in this application, as the same forms the subject-matter of my application, Serial No. 75,654, filed September 16, 1901, of which this application is a division.

I claim as my invention—

1. An outlet-box cover comprising a flat plate having a central opening with an upturned flange, and a plurality of parallel slots near the edge of the plate.

2. An outlet-box having its walls substantially at right angles to its bottom and provided with two or more perforated ears extending in the same plane as the said walls; with a bodily-removable cover having slots to receive the said ears secured to the box by 90 pins.

3. An outlet-box having its walls substantially at right angles to its bottom and provided with two or more perforated ears extending in the same plane as the said walls; 95 with a bodily-removable cover having slots to receive the said ears and an opening in its central part, secured to the box by cotter-pins.

4. An outlet-box struck or drawn up from 100 a single piece of ductile metal, provided with two or more integral ears extending in the same plane as the walls thereof the ears having perforations, as set forth.

5. An outlet-box struck or drawn up from 105 a single piece of ductile metal, provided with two or more integral ears extending in the same plane as the walls thereof, the edges of the walls being ground off smooth, as set forth.

6. The combination of an outlet-box struck or drawn up from a single piece of ductile metal, provided with two or more integral ears extending in the same plane as the walls thereof, the edges of the walls being ground 115 off smooth, and the ears having perforations; a cover made from a single piece of metal having slots adapted to fit over the ears of the box; with spring or cotter pins for the perforations of the ears, as set forth. 120

7. An outlet-box struck or drawn up from a single piece of ductile metal, provided with two or more integral ears extending in the same plane as the walls thereof, the edges of the walls level or ground off as described, and 125 the ears perforated.

In testimony whereof I have signed my name to this specification, in the presence of two subscribing witnesses, this 14th day of January, 1902.

WILLIAM F. BOSSERT.
